RECEPTACLE STAND OR THE LIKE

William R. Beckman, South Bend, Ind., assignor
to The Birdsell Corporation, South Bend, Ind.,
a corporation of Indiana

Application November 15, 1937, Serial No. 174,549

7 Claims. (Cl. 248—152)

My invention relates to tub supports for washing machines or other structures composed of assembled sections and has reference more particularly to facilities for and the method of connecting and reinforcing the sections and securing other parts thereto.

It is desirable in certain structures, for example tub supports for washing machines, to construct same of relatively light gauge sheet metal sections which must be joined together securely and properly reinforced to insure ample strength and rigidity to maintain the desired shape, support the intended load and withstand the strains of any parts connected therewith.

The principal objects of my invention are to provide improved structures, such as tub supports for washing machines composed of assembled sheet metal sections and also an improved method of assembling and reinforcing same; to join the sections in an improved manner which is expeditious and insures a permanent, inseparable connection; to utilize the section joining facilities for reinforcing the assembled structure and attaching other parts thereto; to provide improved means for and an improved method of attaching supports, boxes and other parts to the assembled structure and at the same time increase the inherent strength of the reinforcing facilities; and to make such attachments in a concealed manner without any external evidence thereof, these and other objects being accomplished as described hereinafter and as shown in the accompanying drawing in which,

Fig. 1 is a side view of a washing machine embodying my invention;

Fig. 2 is a horizontal sectional view, on the line 2—2 of Fig. 1, of one of the sections of which the tub support is composed;

Fig. 3 is a side view of one of the section connecting and reinforcing elements;

Fig. 4 is an enlarged sectional view on the line 4—4 of Fig. 3;

Fig. 5 is an enlarged view on the line 5—5 of Fig. 3 of the internal frame connection with the left side of the socket member in section;

Fig. 6 is an enlarged sectional view on the line 6—6 of Fig. 3; and

Fig. 7 is an enlarged bottom view of the lower end of the connecting and reinforcing member of Fig. 3.

In the accompanying drawing I have, for the purpose of illustration shown my invention in connection with a supporting frame for a washing machine, although the invention is not limited thereto, and in this illustrative embodiment

the reference numeral 10 indicates the washing machine tub and 11 the supporting frame as a whole which has a housing 12 at one side which extends up above the top of the tub 10 and has mounted thereon a wringer 13, which, together with the washing instrumentalities of the washing machine is operated by a motor 14 under the tub.

The tub support 11 with which this invention is particularly concerned, is made substantially entirely of a relatively light gauge sheet metal stamped in appropriate quarter sections 15, each of which quarter section has a half leg formation 16 at each end with a connecting web 17 of arcuate form, as shown in Fig. 2, and paneled as at 18 if desired for strengthening and appearance. Above the panel 18 the web 17 may flare outwardly and upwardly as at 19 to an upstanding rim 20 within which is seated the lower end of the tub 10, the bottom contour of which is indicated by the dotted line 21 in Fig. 1.

Each half leg formation 16 is of sufficient length to support the tub 10 at the desired elevation and has an inturned flange 22 at the side which extends throughout the length of the leg formation and has a curled edge 23. This curled edge extends in a straight line from top to bottom of the leg formation 16 and accordingly the flange 22 will be of varying width if the leg formation 16 has a longitudinally curved contour as in the illustrated structure and it will be noted that the upper end of the leg formation is curved inwardly as at 24 to the upstanding flange 20 to close the upper end of the leg formation above the flange 22 and curled edge 23 thereof.

For joining these quarter sections 15 to form an annular tub support, extruded metal bars 25 are employed having an undercut channel 26 along the side with overlying margins 27 along the opposite sides of the channel, said channel being of suitable shape and size to accommodate the curled edge 23 of two adjoining quarter sections 15 when the flanges 22 thereof are arranged in contacting face to face relation as indicated in Fig. 6 and at the right hand end of Fig. 2. Thus in the present structure of four quarter sections four bars 25 are employed and the sections assembled by merely arranging them in end to end relation in annular series so as to form an annular shell with the flanges 22 of the adjoining sections in contacting face to face relation and slipping a bar 25 endwise from the lower end of each pair of leg formations 16 in embracing relation along the out-turned curled edges 23 thereof thereby interlocking the sections

together to form the tub supporting unit, and it will be noted that the upper ends of said bars 25 are covered and concealed by the closed together curved top 24 of the adjoining leg formations 5 and that the bars are concealed throughout their length by their connected leg formations. These bars 25 are of such length that when fully inserted the lower ends thereof are substantially flush with the lower ends of the leg formations 10 and the channels 26 of proper size to embrace the pairs of curled edges 23 tightly therein so that when applied, the flanges 22 are tightly clamped together and the adjoining sections thus rigidly and inseparably joined to form a strong 15 substantial tub support, the legs of which are effectively reinforced throughout their length by the connecting bars.

Obviously any desired number of sections may be employed instead of four quarter sections as 20 shown herein and joined together in like manner with channeled bars 25.

Preferably the bars 25 are of double channeled form each with a channel 28 along the inner side, preferably like the channel 26, for 25 mounting brackets or other fittings on the bars 25, these inside channels 28 being employed in the present structure for mounting tub holders or seats 29, brace connections 30 and caster sockets 31 in appropriate places thereon. Each 30 of these brackets or fittings 29, 30 and 31 has an elongated T-shaped flange 32, of a shape and size to fit snugly in the channel 28, which is slipped into the channel 28 to the proper elevation and locked therein at the selected place. 35 Such locking may be accomplished in any convenient manner, either by squeezing the embracing walls of the channel 28, by means of an appropriate tool, into a sufficiently tight clamping engagement with the respective T flange to lock 40 the flange 32 rigidly therein, or by squeezing the walls of the channel along the unoccupied portions to reduce the size of the channel between and at the ends of the flanges 32 as indicated at 45 33 or by punching the channel walls at the ends of the flanges 32 as indicated at 34, or by providing the flanges 32 with depressions 35 at suitable places and punching the metal of the channel walls therein as indicated at 36. Any one or 50 more of these locking means may be employed, or other means may be employed, although it is preferred to avoid pins and the like which may necessitate providing the bars 25 with openings or apertures which might impair their strength.

These bars 25, being of uniform cross sectional 55 shape throughout their length, may be conveniently made in long lengths by an extruding process and merely cut to proper length, and are of a metal that may be readily shaped to clamp or lock the flanges 32 of the fittings 29, 30 and 60 31 in the channels 28, aluminum being preferably employed, not only because of the advantage of light weight, but also because subsequent shaping thereof as in clamping the flanges of the fittings in the channel or in contracting 65 the channel between and at the ends of the flanges as at 33 not only does not impair the strength thereof but in fact increases the strength and rigidity thereof, thereby enhancing their effectiveness as supporting and reinforcing 70 elements.

Each channel bar 25 has a tub holder or seat 75 29 secured in the channel 28 thereof at the upper end, all being at the same elevation to engage the bottom margin of the tub 10 which is curved as at 37 and the seating faces of the tub

holders 29 being correspondingly curved as shown in Fig. 3 to properly fit same and each channel bar 33 also has a caster socket 31 secured in the channel 28 thereof at the lower end to receive the stem of a caster 39 by which the washing machine is movably supported, said caster sockets being preferably formed with a flange 40 at the bottom engaged under the lower end of the inner half of the channel bar 25 within and concealed by the lower end of the respective leg 10 formations 16.

A frame, part only of which is shown, and indicated as a whole by the reference numeral 41 in Fig. 2, is provided within the assembled washing machine support to brace the assembled 15 structure and provide a mounting for operative parts, and in the present instance comprises a platform portion 42 with a pair of brace bars 43 extending laterally therefrom near each end. Only one end portion of the platform 42 and the 20 brace bars 43 at that end are shown in the drawing, but it is to be understood that the other end of said platform is similarly equipped with two sets of brace bars 43, thus providing four 25 sets of such brace bars 43, each of which said sets is provided at its outer end with a fitting 44 for attachment to a brace connector 30 of the respective channel bar 25, thereby interlocking the four channel bars to frame 41.

Each fitting 44 is provided at its outer end with 30 a vertically extending pintle like formation 45, preferably with rounded upper and lower ends and circumferential grooves 46 and each brace connector 30 is provided with a correspondingly elongated stirrup 47 with a substantially cylindrical opening 48 therethrough open along the inner side to receive the formation 45 of the fitting 44 endwise therein. The walls of the stirrup 47 are malleable and after the formation 45 has been inserted in the opening 48 the stirrup 40 walls are contracted by means of a suitable tool to engage the rounded end of the formation 45 and the grooves 46 thereof so as to lock the formation 45 securely and permanently in the contracted opening 48 of the stirrup 47, thereby 45 securing the frame 41 likewise securely and permanently within the tub support and insuring a strong and effective bracing of leg formations thereof.

The housing 12 by which the wringer is supported and through which driving connections therefor are provided from the motor 14 is preferably secured to the side of the tub support, preferably between a pair of leg formations of one of the sections 17 as indicated in Fig. 2 and 55 55 may be secured to such section in any convenient manner, and suitable openings will of course be provided through the wall of the section 17 from within the tub supporting structure to the interior of the housing 12 for power communication, the particular manner of attachment of the housing 12 to the section 17 and the arrangement of such openings thereto not being particularly shown as they form no part of the present invention.

From the foregoing it will be apparent that I have provided a construction and a method which may be advantageously employed in making tub supports for washing machines and other similar structures of assembled sheet metal sections—that the assembling of the sheet metal sections is greatly facilitated and the sections and other parts are securely and rigidly united in a manner to obviate any release or relaxation of the connections such as occur when bolts or 70 75 80 85 90 95 98

other similar fastenings are employed; that all connections are made with reinforcing members so that no strain is imposed thereby on the sheet metal parts and in such a manner that 5 there are no exposed connections or connecting means; that the connecting means for the sheet metal sections serve at the same time to effectively reinforce the assembled structure and are of such a character that their strength and 10 rigidity is increased by the shaping thereof in the preferred manner of attaching parts thereto, and it is to be noted that the manner of attaching fittings to the channeled reinforcing members permits location thereof at elevations 15 selected at the time of attachment without the necessity of previously shaping, drilling or otherwise preparing the parts for attachment of the fittings at a selected location.

While I have shown and described my invention in a preferred form, I am aware that various changes and modifications may be made therein without departing from the principles of my invention, the scope of which is to be determined by the appended claims.

25 I claim as my invention:

1. A receptacle stand or the like comprising a plurality of substantially arcuate sheet metal sections joined together consecutively in the form of an annular shell, each section having a leg 30 extension at each end combined with a corresponding leg extension of the adjacent section to form a supporting leg for the assembled structure, an elongated member extending along and joining the adjoining leg extensions and 35 having a channel extending lengthwise thereof at the inner side, and a frame within the shell having fittings engaged in the said channels of said members.

2. A receptacle stand or the like comprising 40 a plurality of substantially arcuate sheet metal sections joined together consecutively in the form of an annular shell, each section having a leg extension at each end combined with a corresponding leg extension of the adjacent section 45 to form a supporting leg for the assembled structure, an elongated member extending along and joining the adjoining leg extensions and having 50 a channel extending lengthwise thereof at the inner side, and a frame within the shell having fittings engaged in the said channels of said members, the walls of said channels being deformed to lock the said fittings therein.

3. A receptacle stand or the like comprising a 55 plurality of substantially arcuate sheet metal sections joined together consecutively in the form of an annular shell, each section having a leg extension at each end combined with a corresponding leg extension of the adjacent section to form a supporting leg for the assembled structure, each of said adjoining leg extensions having a flange therealong extending inwardly of the shell, a connecting member extending along the flanges of the adjoining leg extensions and having 60 two channels within one of which said flanges are interlocked, said connecting members having seat members secured in their other channels at

the upper end thereof and extending inwardly of the shell to support a receptacle in the upper end of the enclosure.

4. A receptacle stand or the like comprising a plurality of substantially arcuate sheet metal sections joined together consecutively in the form of an annular shell, each section having a leg extension at each end combined with a corresponding leg extension of the adjacent section to form a supporting leg for the assembled structure, each of said adjoining leg extensions having a flange therealong extending inwardly of the shell, a connecting member extending along the flanges of the adjoining leg extensions and having two channels within one of which said flanges are interlocked, said connecting members having 15 caster sockets secured in their other channels at the lower end thereof and a caster engaged in each caster socket.

5. A receptacle stand or the like comprising a plurality of substantially arcuate sheet metal sections joined together consecutively in the form of an annular shell, each section having a leg extension at each end combined with a corresponding leg extension of the adjacent section to form a supporting leg for the assembled structure, each of said adjoining leg extensions having a flange therealong extending inwardly of the shell, a connecting member extending along the flanges of the adjoining leg extensions and having two channels within one of which said flanges are interlocked, said connecting members having 20 a plurality of spaced fittings secured in the other channel of each connecting member, a receptacle supported on the uppermost fitting of each connecting member, a caster 25 engaged in the lowermost fitting of each connecting member, and a frame within the shell and secured to an intermediate fitting of each connecting member.

6. A receptacle stand or the like comprising a plurality of sheet metal sections joined together consecutively in the form of an annular shell, each section having at each end a leg extension combined with a leg extension of the adjoining section to form a supporting leg for the shell, 40 said leg extensions being secured together throughout their length to hold the sections in assembled relation and said annular shell being formed with an internal annular seat at the top, each leg extension having a reinforcing member 45 extending upwardly to and provided at said annular seat with a seating member in cooperative seating relation with the annular seat.

7. A receptacle stand or the like comprising a plurality of sheet metal sections joined together consecutively in the form of an annular shell, each section having at each end a formation combined with a similar formation of the adjoining section to constitute an external pilaster like member and supporting leg at the juncture 55 of the sections, and section joining means within and extending substantially throughout the length of the pilaster like member and supporting leg.

WILLIAM R. BECKMAN. 65
